[57] CLAIM

The ornamental design for a nail holding attachment for a hammer head, as shown and described.

DESCRIPTION

FIG. 1 is a front perspective view of a nail holding attachment for a hammer head showing my new design; FIG. 2 is an elevational view of one side thereof, the opposite side being a mirror image;

FIG. 3 is an elevational view of one end thereof, the opposite end being a mirror image;

FIG. 4 is a top plan view thereof; and,

FIG. 5 is a bottom plan view thereof.

The broken line representation of a hammer head and nail in FIG. 2 is for the purpose of illustrating the environment and forms no part of the claimed design invention.

FIG. 1.

FIG. 2.

FIG. 3.

FIG. 4.

FIG. 5.
